(57) **CLAIM**

The ornamental design for a broadhead having both pivoting and fixed blades, as shown and described.

DESCRIPTION

FIG. 1 is a perspective view of an embodiment of a broadhead having both pivoting and fixed blades illustrated with the pivoting blades fully retracted;

FIG. 2 is a perspective view of the broadhead of FIG. 1 with the pivoting blades partially deployed;

FIG. 3 is an illustration of the broadhead of FIG. 1 in a dis-assembled state;

FIG. 4 is a plan view of the broadhead of FIG. 1;

FIG. 5 is a plan view of the broadhead of FIG. 1 as viewed orthogonally from the plan view illustrated in FIG. 4;

FIG. 6 is an illustration of the broadhead of FIG. 5 with the pivoting blades partially deployed;

FIG. 7 is an illustration of the broadhead of FIG. 5 with the pivoting blades partially deployed;

FIG. 8 is an illustration of the broadhead of FIG. 5 with the pivoting blades fully deployed;

FIG. 9 is an elevation view of the broadhead of FIG. 7 as viewed from the end opposite the tip of the broadhead;

FIG. 10 is an elevation view of the broadhead of FIG. 7 as viewed from the tip of the broadhead;

FIG. 11 shows the locations for the cross-sectional views illustrated in FIGS. 12-16 for the broadhead of FIG. 4 without the pivoting blades;

FIG. 12 is a cross-sectional view of the broadhead of FIG. 11 along the line 12-12;

FIG. 13 is a cross-sectional view of the broadhead of FIG. 11 along the line 13-13;

FIG. 14 is a cross-sectional view of the broadhead of FIG. 11 along the line 14-14;

FIG. 15 is a cross-sectional view of the broadhead of FIG. 11 along the line 15-15;

FIG. 16 is a cross-sectional view of the broadhead of FIG. 11 along the line 16-16;

(Continued)

FIG. 17 is a perspective view of another embodiment of a broadhead having both pivoting and fixed blades, and a helical tip, illustrated with the pivoting blades fully retracted;

FIG. 18 is a perspective view of the broadhead of FIG. 17 with the pivoting blades partially deployed;

FIG. 19 is an illustration of the broadhead of FIG. 17 in a dis-assembled state;

FIG. 20 is a plan view of the broadhead of FIG. 17;

FIG. 21 is a plan view of the broadhead of FIG. 17 as viewed orthogonally from the plan view illustrated in FIG. 20;

FIG. 22 is an illustration of the broadhead of FIG. 21 with the pivoting blades partially deployed;

FIG. 23 is an illustration of the broadhead of FIG. 21 with the pivoting blades partially deployed;

FIG. 24 is an illustration of the broadhead of FIG. 21 with the pivoting blades fully deployed;

FIG. 25 is an elevation view of the broadhead of FIG. 23 as viewed from the end opposite the tip of the broadhead;

FIG. 26 is an elevation view of the broadhead of FIG. 23 as viewed from the tip of the broadhead;

FIG. 27 shows the locations for the cross-sectional views illustrated in FIGS. 28-32 for the broadhead of FIG. 20 without the pivoting blades;

FIG. 28 is a cross-sectional view of the broadhead of FIG. 27 along the line 28-28;

FIG. 29 is a cross-sectional view of the broadhead of FIG. 27 along the line 29-29;

FIG. 30 is a cross-sectional view of the broadhead of FIG. 27 along the line 30-30;

FIG. 31 is a cross-sectional view of the broadhead of FIG. 27 along the line 31-31; and,

FIG. 32 is a cross-sectional view of the broadhead of FIG. 27 along the line 32-32.
